(57) **CLAIM**

The ornamental design for a chair, as shown and described.

DESCRIPTION

FIG. 1 is an isometric view of an ornamental design of a first embodiment of a chair showing our new design;

FIG. 2 is a front orthographic view thereof;

FIG. 3 is a rear orthographic view thereof;

FIG. 4 is a right side orthographic view thereof;

FIG. 5 is a left side orthographic view thereof;

FIG. 6 is a top orthographic view thereof; and,

FIG. 7 is a bottom orthographic view thereof.

The broken lines shown in FIGS. 1-7 are for illustrative purpose only and form no part of the claimed design.

The fragmented crosshatching shown on the front backrest member in FIGS. 1 and 2 is understood to represent mesh fabric and would be continuous throughout the circumscribed areas.
